UNITED STATES PATENT OFFICE.

VINCENT G. APPLE, OF DAYTON, OHIO.

COMMUTATOR.

1,032,802.

Specification of Letters Patent.

Patented July 16, 1912.

Application filed March 10, 1911. Serial No. 613,640.

To all whom it may concern:

Be it known that I, VINCENT G. APPLE, a citizen of the United States, residing at Dayton, in the county of Montgomery and 5 State of Ohio, have invented certain new and useful Improvements in Commutators, of which the following is a specification.

My invention relates to improvements in commutators for dynamo-electric machines. 10 One of the objects of my invention is to provide a commutator wherein the parallel segments are spaced apart, to thereby afford intervening air spaces, and means for inducing air drafts through said spaces, whereby 15 said segments, or bars, and the brushes bearing thereon, are maintained at a relatively low temperature, and the process of commutation greatly improved, and whereby comminuted, electrically conducting particles worn from the commutator and brushes are blown away by the drafts of air superinduced by my improved construction, thereby preventing short-circuiting by accumulation of said particles upon the insulated parts of said commutator and brush-supporting surfaces. 20 25 30

Other and further objects of my invention will be readily apparent from a consideration of the specification taken in conjunction with the drawing wherein;

Figure 1 is a longitudinal central section showing one half of said commutator. Fig. 2 is a transverse section taken on line 2—2 of Fig. 1. Fig. 3 is a fragmentary, transverse section, taken on line 3—3 of Fig. 1. Fig. 4 shows a cross-section view of a modified form of construction.

An armature shaft 5 is shown broken away at each end. The armature is to be 40 carried on said shaft on the end to the left, if the shaft were not broken away, and a bearing is contemplated for the other end, as usual in such structures.

A sleeve 6 is provided with an integral 45 flange disk 7, flanged as at 8 and secured to the shaft 5 by a key or feather 10, seated in a key-way 11 made in the shaft and in like manner in the sleeve. The sleeve 6 is screw threaded as at 12 for nuts 13 and 14. 50 A follower disk 15 slides freely over the threaded end of the sleeve 6 and is flanged as at 16.

A series of commutator segments, or bars

17, are tapered at each end, as at 18, and to 55 these bars the conducting wires of the armature are to be respectively connected, as usual in such structures.

Disks of insulating material 19, of which there are two, that may be substantial duplicates are provided with sockets 20, tapered to correspond with and for proper seating of the tapered ends 18 of the bars 17. Separators 21, are provided between adjacent sockets, and serve as means for spacing the 60 bars apart to thereby provide air spaces 22 between adjacent bars, shown somewhat exaggerated in Fig. 2 for clearness of illustration. The separators, it will be observed, continue along the tapered ends of the bars, 65 70 the full distance of the taper thereby providing a stanch lateral support for the bars without shutting off any of the active surface of the commutator from the free action of the air.

75 Grooves are provided between the shaft 9 and the sleeve 6, parallel to the axis thereof, as a means for admitting air, and radial holes 23 are made through the wall of the sleeve at intervals, to permit the air to pass 80 within the commutator housing 26. The longitudinal grooves, 24, of which there may be any desirable number, may be made internally of the sleeve, as shown in Fig. 2, or externally of the shaft, as shown in Fig. 4. 85

The operation of the device is as follows: When the commutator is being rotated at a high velocity the effect of centrifugal action is to throw the air out between the commutator bars, such parts of the structure traveling at a higher rate of speed than the parts nearer the axis, air will be drawn into the grooves 24, as at 25, pass through said grooves into and through the transverse holes 23 into the housed space 26 and then 90 out between the commutator bars. This action produces a considerable draft of air, 95 which effects a rapid change of air, and thereby carrying away from the commutating parts any abnormal heat that may be 100 engendered thereby, and causing the free, small conducting particles, due to commutation to be blown away, thus keeping the commutator parts cool and clean.

105 While I have herein described a single embodiment of my invention, it is evident that many changes in the structure may be made

from the specific showing, and within the scope of the appended claims without departure from the spirit of the invention.

Having described my invention, what I claim is;

1. In combination with a commutator having a plurality of commutator bars, tapered at their ends, circumferentially arranged and spaced apart and housing means therefor, of two disks of insulating material one for each end of said bars; said disks provided with pockets for the ends of said bars, and integral separating spacing shoulders between said pockets.
- 15 2. In a commutator, a plurality of commutator bars, tapered at their ends, circumferentially arranged and spaced apart to

provide air spaces therebetween, disks of insulating material for each end of said bars; said disk provided with pockets for the ends 20 of said bars, and separating, spacing shoulders between said pockets, and a housing structure, for supporting said insulating disks, said housing structure provided with an air aperture nearer the axis of said commutator than are said bars for inducing a draft of air through said commutator when rotated.

In testimony whereof I hereunto set my hand in the presence of two witnesses.

VINCENT G. APPLE.

In the presence of—

H. E. BORGER,
N. E. SNYDER.
